DENTAL OPERATING LAMP

Alphonse F. Pieper, Rochester, N. Y.

Application November 30, 1932, Serial No. 645,079

9 Claims. (Cl. 240—41.15)

The present invention relates to light projecting apparatus such, for example, as that employed in the performance of dental work and has for its object to provide improvements in apparatus of this class whereby to increase its efficiency and serviceability as well as to render it convenient to operate and economical to manufacture.

A further object of the invention is to provide an improved operating lamp capable of adjustment to various operating positions and designed for the illumination of different parts or objects to be inspected or operated upon and being particularly useful in the practice of dentistry where it is desired to provide effective illumination of the oral cavity during treatment of the teeth or in the performance of surgical operations.

A further object of the invention is to provide a dental lamp embodying a simplified, efficient and unitary construction providing for the complete enclosure of the electrical connections and designed to facilitate the circulation of air through the lamp to effectively cool the parts which become heated during operation.

A further object of the invention is to provide in combination with a light projecting operating lamp for use in the performance of dental, surgical and other kinds of work, a combined eye shield and holder adjustable to different positions upon the lamp and adapted to support different objects or articles for illumination by the lamp, such for example as a data sheet, or a film or translucent element containing an image of the part to be treated or operated upon in order that it may be readily inspected or viewed by the operator.

A further object of the invention is to provide an improved shield or visor which can be readily applied to or detached from the lamp when desired and which can be adjusted to various service positions in advance of the lamp to protect the patient from the glare of the light.

A further object of the invention is to provide in combination with a dental lamp of the class described, improvements by which to control the lamp circuit for the purpose of varying the intensity of the light or producing a relatively bright or dim light as may be required under different operating conditions.

Another object of the invention is to provide improved counterbalanced supporting means for the lamp together with connections affording universal movement of the parts whereby to insure ease of operation, maximum adjustability, and the poising or balancing of the lamp at whatever position it may be desired to operate the same.

To these and other ends the invention resides in certain improvements and combinations of parts, all as will be hereinafter more fully described, the novel features being pointed out in the claims at the end of the specification.

In the drawings:

Fig. 1 is a view in elevation embodying one form of the invention;

Fig. 2 is a fragmentary part sectional elevation of the counterbalanced supporting means for the lamp and associated parts;

Fig. 3 is a fragmentary part sectional view illustrating the universal joint by which the counterbalancing mechanism is supported;

Fig. 4 is a fragmentary sectional elevation through the ball and socket joint for connecting the lamp with the counterbalancing mechanism;

Fig. 5 is a view showing the lamp and the eye shield or visor attached thereto;

Fig. 6 is a longitudinal section through the lamp and visor shown in Fig. 5, drawn to an enlarged scale;

Fig. 7 is a side elevation of the visor and its supporting ring;

Fig. 8 is an end elevation of the same; 80

Fig. 9 is a diagrammatic arrangement of the lamp circuit and the switch for controlling the same;

Fig. 10 is a side elevation of the lamp with the visor removed; 85

Fig. 11 is a front end elevation of the same drawn to a somewhat enlarged scale; and

Fig. 12 is an enlarged sectional elevation through the lamp and the resistance surrounding the lamp socket. 90

The same reference numerals throughout the several views indicate the same parts.

Referring to the drawings, the lamp is indicated generally at 10 and is supported for universal movement upon the counterbalanced mechanism indicated generally at 11 which in turn is mounted for universal movement upon a bracket 12 carried by a suitable support 12a as shown in Fig. 1, and more fully described hereinafter. 95

The lamp casing is formed of inner and outer sections 13 and 14, respectively, each of which comprises a one piece construction whereby the usual method of joining several parts together to complete one or more sections in lamps of this type, is avoided. The inner section terminates short of the ends of the outer section and is supported throughout its length in spaced relation to the outer section to afford an air circulating passage 15 between the sections, the outer section being open at all times to permit of the passage of the air around the inner section. Circulation of the air through the outer section is provided for by the openings 16 and 17 in the front and 105

rear ends of the outer section, as shown in Figs. 10 and 12. By circulating the air through the passage 15 and the openings 16 and 17, both sections and the several parts therein, including the lamp socket and the resistance, are prevented 115

100

105

110

115

120

from becoming heated to any appreciable degree.

The inner section of the lamp is supported by means of a plurality of transversely extending spacing members 18 suitably connected with the sections, as by means of the screws 19. The inner section has a parabolic reflecting face 20 for directing the light rays of the lamp 21 outwardly through the ends of the sections, the lamp being screwed into a socket 22 disposed in the rear portion of the outer section 14. The socket is supported preferably by a yoke or bracket 23 having an annular portion 24 thereon provided with a threaded extension 25 projecting through the rear end of the outer casing 14. A nut 26 is screwed into position upon the extension 25 to clamp the yoke in position. A handle 27 is also screwed upon the extension for adjusting the lamp to different positions, the lamp being mounted for universal movement upon the counterbalancing means in a manner described hereinafter.

The front end of the inner section of the lamp casing is provided with an enlarged annular portion 28 having a shoulder 29 at its base, on which is seated a light diffusing and color modifying element 30 which may be of glass or other light transmitting material tinted or colored, preferably to simulate daylight. In front of the element 30 is a light controlling or projecting lens 31 of any suitable type which is held in position by a split ring 32 formed of spring material and detachably secured within the groove of a bead-like portion 33 formed on the annular portion 28 of the lamp casing 13.

Means has been provided within the lamp casing, in conjunction with the lamp circuit, for varying the intensity of the light as may be required from time to time. This means comprises a resistance element 34 extended about a tubular support 35 surrounding the lamp socket, as shown in Fig. 12. The tubular member is supported by a closure 36 at its outer end, between which and the end wall of the lamp casing is a spacing element 37 of insulating material. A layer of insulating material 39 is also interposed between the tubular support 35 and the resistance 34, and the latter is protected and held in position by a covering 40 of insulating or other suitable material.

A two-way switch for controlling the lamp circuit is indicated generally at 41 and is supported within the outer section of the casing upon the wall thereof. The switch comprises a movable contact 42 having an operating portion 43, the movable contact having two closing positions in which it engages one or the other of two sets of fixed contacts 44 and 45. The off position of the movable contact is indicated by dotted lines in Fig. 9. However, any other suitable or preferred type of two-way switch may be substituted for the one shown.

The circuit wires or connections shown in Fig. 9 are carried through the lamp supporting members as described hereinafter and are extended within the lamp casing and connected with the lamp socket, the switch and the resistance all of which parts are housed within the casing.

In a diagram of the circuit shown in Fig. 9 the movable contact is indicated at the position to which it is shifted to effect dimming of the light, in which position the current will flow through wire 46, lamp 21, resistance 34, switch contacts 44 and 42 and wires 47 and 48. In the other closing position of the switch, the current will flow through wire 46, lamp 21, wire 49, switch contacts

45 and 42 and wires 50 and 48, in which position of the parts the lamp will be illuminated to its full intensity. Thus provision is made for the use either of a bright or a dim light as the nature of the work may require, as for example where there may be a considerable difference in the density of the data sheets or other objects to be considered.

The means for protecting the patient from the glare of the light when under treatment comprises a shield or visor having a main or body portion 51 provided with angularly disposed end portions or wings 52, as best shown in Fig. 6. The visor is provided at its inner edge with spaced bearing portions 53 for receiving a pivot member 54 carried by the bearings 55 of a bracket 56 rigidly connected with the central portion of a split ring 57 formed of resilient or spring-like material. The shield or visor may be swung to various angular positions upon the ring in all of which it is held by a spring-like tongue 58 on the bracket through frictional engagement of the tongue with the pivot member 54. The split ring 57 is mounted within a channel shaped bearing or guideway 14a formed on the front end of the outer section 14 of the lamp casing as shown in Figs. 6 and 12, thus permitting the ring and the shield thereon to be rotated upon the casing around the longitudinal axis of the lamp whereby to adjust the shield to different service positions on the casing, depending upon the position at which the lamp is to be operated.

Means is provided upon the shield for supporting the data sheets or other image bearing objects at a suitable point in front of the lens 31 for illumination by the light transmitted thereby. This means preferably comprises a pair of spring clips 59 adapted to receive the sheets 60 as indicated in Fig. 6. The clips are provided with rearwardly extending portions 61 seated upon and connected with the wings 52 of the eye shield, preferably by means of the screws 62. The wings are designed to extend into the end of the lamp casing and are curved to conform substantially to the curvature of the enlarged annular portion 14a of the casing whereby light is prevented from escaping past the ends of the shield when it is in the position shown by full lines in Fig. 6. The dotted line position of the shield indicated in this figure is that to which it is adjusted when the film or data sheet is attached thereto as an aid to the dentist or surgeon in determining the condition and the particular location of the part to be treated or operated upon. It will be understood that the data sheet can be supported in position to be illuminated by the lamp rays at the same time that the lamp is being used to project the light into the mouth of the patient, or to illuminate other parts requiring treatment, it being understood that the nature of the object to be illuminated and the purpose of displaying the same may vary from time to time depending upon the character of the work under consideration.

One advantage of providing means for varying the intensity of the light is to accommodate it to objects or data sheets, the images on which may vary in clearness or distinctiveness to a considerable degree. In this connection it will be understood that where the data sheets 60 or other translucent elements are relatively dense and the images thereon more or less obscure the movable contact of the switch will be shifted to the closing position in which the resistance is cut out, whereby a relatively bright light will be afforded by which to view the sheets. On the other hand

if a sheet or other object is to be used on which the image is relatively clear or distinct, better results may be obtained by dimming the light and in such cases the switch will be moved to the 5 position in which the resistance will be included in the circuit. However, it will be understood that the intensity of the light may be varied from time to time as required by the nature of the work regardless of whether or not the character 10 of the latter makes it necessary or desirable to use the data sheets or other image bearing objects.

A ball and socket joint is provided between the lamp casing 14 and the supporting means 15 therefor, which in the present illustration comprises the counterbalanced supporting mechanism indicated generally at 11, in Figs. 1 and 2. The ball and socket joint comprises a tubular socket member 63 secured upon the wall of the 20 casing by a clamping ring 64 engaging the inner face of the casing and threaded within the socket member to clamp it upon the outer wall of the casing. The outer end of the socket member is shaped to receive the ball-like portion 65 of a tubular member 66 for supporting the lamp, which 25 in turn may be supported by any suitable means but which is preferably connected with and supported by the counterbalanced mechanism as described hereinafter.

30 A member 68 is positioned within the tubular member 63 to complete the socket portion of the joint and is urged into engagement with the ball-shaped member 65 by a spring 69, the inner end of which engages a retaining member 70 threaded within the ring 64 as shown in Fig. 4. The 35 socket member 68 is prevented from turning by a screw 71 threaded within the wall of the member 63 and having its inner end reduced and projected within a slot 72 formed in the socket member 68 whereby the latter is free to move longitudinally within the tubular member 63. The ball-shaped member 65 is provided with an annular groove 73 into which projects the reduced end of a screw 74 threaded within the wall of 40 the socket member 63 for cooperation with a pin 75 secured within the groove to limit the extent of rotation of the lamp around the axis of the supporting member 66 whereby to prevent undue twisting of the circuit connections extending through the ball and socket joint into 45 the lamp casing as shown in Fig. 4.

The counterbalanced mechanism for supporting the lamp in various operating positions comprises a tubular arm 76 from which extends the 50 lamp support 66. The inner end of the arm is provided with a flattened portion 77 extended between the outer ends of a pair of twisted links 78, the inner ends of the links having disposed therebetween the flattened portion 12b of the 55 horizontally disposed portion of the support 12. The links, at their opposite ends, are provided with annular bearing surfaces 79, those at the outer ends of the links rotatably receiving the flattened portion 77 of the arm 76 and those at 60 the inner ends of the links being rotatable upon the flattened portion 12b of the support 12 as shown in Fig. 1.

The opposite ends of the links are connected 65 one with another by the members 80 and 81, the latter being threaded into the former as shown in Fig. 3. A sleeve 83 is positioned upon the screw 81 to protect the circuit wires or conductors carried through the links which are preferably looped around the sleeve as shown in Fig. 75

3. The arm 76 and the support 12 are thus connected together in a manner to permit of universal movement of the arm and the lamp carried thereby. The vertical portion of the support 12 is sleeved within the bracket 12a 80 which is adapted to be clamped upon a suitable support, not shown, the bracket being of tubular construction to accommodate the circuit connections which are carried upwardly therethrough and through the support 12, the links 78, the arm 76 and the socket member 63 into the lamp casing where they are connected with the lamp, the switch and resistance as shown diagrammatically in Fig. 9.

The counterbalancing means for the lamp is interposed between the outer end of the arm 76 and one of the links 78 and comprises a tubular member 84 having at its lower end an extension 85 pivotally connected at 86 with an upstanding lug 87 on the upper link 78 as indicated in Figs. 1 and 2. Slidably mounted within the outer end of the tube 84 is a tubular member 88 into which is threaded a connection 89 which is pivoted at 90 upon a collar 91 fixed on the arm 76 by means of a screw 92. Mounted within the tubular members 84 and 88 is a counterbalancing spring 93 the outer end of which is anchored upon the inner end of the connection 89. Suitably connected with the spring is a member 94 within which is threaded a screw 95 extending 105 through and rotatable in the connection 85 for adjustment to effect tensioning of the spring whereby to insure proper counterbalancing of the lamp and associated parts.

It will be understood that the counterbalancing 110 means will operate to maintain the arm 76 and lamp thereon at the different positions to which they may be adjusted in a vertical direction about the horizontal axis of the links 78. It will be understood that the difference in torque of the 115 lamp supporting arm in the different positions to which it is adjusted in a vertical direction is compensated for by the spring means when the latter is properly tensioned. In other words, upon lowering the arm from the position shown 120 in Fig. 1 the force exerted by the weight of the lamp is increased by reason of the increase of the leverage of the arm in moving toward a horizontal position. As the arm is moved downwardly the increase in the tension of the spring will 125 correspond substantially to the increase in the torque of the arm thus causing the parts to be balanced at the different positions to which they may be adjusted.

In the operation of the lamp the switch thereon 130 may be moved to afford either a bright or a relatively dim light as the nature of the work may require regardless of whether or not use is to be made of the film or data sheet holder, which is provided for use at such times as it may be advantageous or desirable to employ the same.

Furthermore the visor may be easily rotated upon the front of the lamp around the axis thereof to adjust it to eye shielding position regardless of the angular position of the lamp with respect 140 to the patient, which will necessarily vary from time to time under different operating conditions.

Adjustment of the eye shield to move the data sheet thereon into position to be illuminated by the lamp, as indicated by dotted lines in Fig. 6 145 is effected by swinging it upon its pivot outwardly in a direction away from the axis of the lamp, it being swung toward said axis when returning it to normal eye shielding position.

Furthermore, if the dentist is required to shift 150

from one side of the patient to another, the position of the visor can be correspondingly changed merely by rotating it about the axis of the lamp. On the other hand, if at times it is desired to utilize all of the lamp rays, the visor can readily be moved to an out of the way position at one side of the lamp casing merely by swinging it outwardly upon its pivot.

The advantage of providing for universal movement of the counterbalancing means will be apparent and the same is true with respect to the mounting of the lamp for universal movement upon the counterbalancing mechanism since with these different adjustments the lamp may be quickly moved to whatever position it may be desired to operate the same. The handle on the lamp greatly facilitates adjustment of the same to the desired position and makes it unnecessary for the operator to place the hand upon the lamp casing, thereby avoiding any discomfort which might be occasioned by touching the latter which may become heated to a slight degree when in use.

The placing of the switch directly on the lamp casing renders it extremely convenient to the operator, who does not have to shift his position when turning on or off the light or when dimming the same.

The circulation of air throughout the length of the lamp casing in contact with the inner and outer walls thereof and around the socket and the resistance serves to rapidly cool the parts, thus preventing them from becoming heated to any appreciable degree.

The lamp is of a compact and unitary design embodying a single housing element within which is mounted the light transmitting and reflecting means, the lamp and lamp socket, and the switch, together with the resistance, all of which parts are detachably secured within the housing for removal through the open end thereof. The several parts enumerated can be easily assembled in proper position and the eye shield readily applied to the housing and removed therefrom. This arrangement effects a saving in the cost of materials and workmanship and affords a practical and efficient construction.

I claim:

1. In an operating lamp, a lamp casing having a lamp therein, a lens on the casing for projecting the lamp rays in advance thereof, a part extending forwardly of the casing, and a data sheet holder on said part adapted to support the sheet in front of and spaced from the lens in position to directly intercept the lamp rays passing through the lens.

2. In an operating lamp, a lamp casing, a light projecting lens supported by the casing, a member rotatable upon the casing around the axis of the projected beam, and a holder on said member spaced from and in advance of the casing adapted to support a data sheet in position to directly intercept light rays passing through the lens, the data sheet upon rotation of said member being adapted to occupy different positions directly in front of the lens.

3. In an operating lamp, a lamp casing, a lens supported by the casing for projecting light rays in advance thereof, a member rotatable upon the casing around the axis of the projected beam, and a device including a data sheet holder mounted to move upon said member to move the sheet to different angular positions with respect to the lens.

4. In an operating lamp, a lamp casing, a lens supported by the casing for projecting light rays in advance thereof, a device mounted to swing upon the casing to different angular positions with respect to the lens, and a holder for a data sheet secured on said device adapted in one position thereof to support the sheet in position to be illuminated by the light rays passing through the lens.

5. In an operating lamp, a lamp casing, a light projecting lens supported by the casing, an element associated with the lens for modifying the color of the light projected thereby, a member rotatable upon the casing around the axis of the lens, and a data sheet holder movable on said member to different angular positions with respect to the lens, in one of which positions the sheet is adapted to be illuminated by light rays passing through the lens.

6. In an operating lamp, a lamp casing having an annular guideway formed interiorly of its front end, a light projecting lens within the casing, a member rotatably supported within said guideway and having a part extending in advance of the lens, and an eye shield extending in advance of and mounted for adjustment upon said part to different angular positions relative to the lens, said eye shield having a body portion provided with angularly disposed wings extending inwardly of the front end of the casing in one position of the eye shield.

7. In an operating lamp, a lamp casing having an annular guideway formed interiorly of its front end, a light projecting lens within the casing, a member rotatably supported within said guideway, an eye shield hinged upon said member to swing to different angular positions with respect to the lens, and a data sheet holder on the eye shield adapted to support the sheet in angular relationship with respect to the eye shield and in position to be illuminated by the light rays passing through the lens.

8. In an operating lamp, a lamp casing, a reflector within the casing, a lamp within the casing extending within the reflector, a lens within the casing in advance of the reflector, an eye shield connected with the casing for a swinging movement toward and from the axis of the lens, and a holder on the eye shield adapted to support a data sheet in depending relation with respect thereto, said sheet in one position of the holder adapted to directly intercept light rays projected through the lens.

9. In an operating lamp, a lamp casing open at its front end, said end having an annular guideway formed therein, a reflector within the casing terminating short of the guideway, a light projecting lens mounted on the reflector independently of the casing and spaced in rear of the guideway, a lamp socket within the casing adapted to support a lamp within the reflector, a split ring disposed rearwardly of the front end of the casing and rotatably seated in said guideway in spaced relation to the reflector and the lens and free to rotate within the guideway, and an eye shield in advance of the casing and pivotally connected with the ring for rotation around the axis of the projected beam and adapted to swing upon the ring toward and away from said axis.

ALPHONSE F. PIEPER.
